DESIGN FOR AN ELECTRIC FLASHLIGHT

Robert E. Bourke, Chicago, Ill., assignor to Sears, Roebuck and Co., Chicago, Ill., a corporation of New York

Application July 27, 1940, Serial No. 93,965

Term of patent 7 years

To all whom it may concern:

Be it known that I, Robert E. Bourke, a citizen of the United States of America, residing at Chicago, in the county of Cook and State of Illinois, have invented a new, original, and ornamental Design for an Electric Flashlight, of which the following is a specification, reference being had to the accompanying drawing, forming a part thereof.

Fig. 1 is a side elevational view of the electric flashlight, showing my new design;

Fig. 2 is an elevational view of the left end of Fig. 1; and

Fig. 3 is an elevational view of the right end of Fig. 1 with the switch and switch-plate omitted for convenience of illustration.

The dominant features of my design reside in the portions shown in full lines.

I claim:

The ornamental design for an electric flashlight, substantially as shown and described.

ROBERT E. BOURKE.
